US0D1047978S

(12) **United States Design Patent** (10) Patent No.: **US D1,047,978 S**
(45) Date of Patent: ** Oct. 22, 2024

(54) **EARPHONE**

- (71) Applicant: **Apple Inc.**, Cupertino, CA (US)
- (72) Inventors: **Ryan Ott**, North Hollywood, CA (US); **Robert Boyd**, Los Angeles, CA (US); **Duy P. Le**, Venice, CA (US); **Jeffrey Scott Croyle**, San Francisco, CA (US); **Matthew Phillip Casebolt**, Fremont, CA (US); **Matthew Vincent Costello**, Soquel, CA (US); **James Swasey**, Oakland, CA (US); **Guillaume Raoult**, San Francisco, CA (US); **Christopher Kuh**, San Francisco, CA (US); **Robert Brunner**, Glen Ellen, CA (US)
- (73) Assignee: **Apple Inc.**, Cupertino, CA (US)
- (**) Term: **15 Years**
- (21) Appl. No.: **29/880,712**
- (22) Filed: **Jul. 26, 2023**

Related U.S. Application Data

- (63) Continuation of application No. 29/850,597, filed on Aug. 22, 2022, now Pat. No. 995,490, and a continuation of application No. 29/763,656, filed on Dec. 23, 2020, now Pat. No. Des. 961,555.

(57) **CLAIM**

The ornamental design for an earphone as shown and described.

DESCRIPTION

FIG. 1 is a top perspective view of an earphone showing the claimed design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The broken lines in the figures show portions of the earphone that form no part of the claimed design.

1 Claim, 4 Drawing Sheets
